H. W. SMALL

WRENCH

Filed Apr. 1, 1921

Inventor
wall.

Attorney.

UNITED STATES PATENT OFFICE.

HERVEY W. SMALL, OF SMALL, IDAHO.

WRENCH.

Application filed April 1, 1921. Serial No. 457,677.

To all whom it may concern:

Be it known that I, HERVEY W. SMALL, a citizen of the United States, residing at Small, in the county of Clark, State of Idaho, have invented certain new and useful improvements in Wrenches; and I do hereby declare the following to be a full, clear, and exact description of the invention, such as will enable others skilled in the art to 10 which it appertains to make and use the same.

This invention relates to new and useful improvements in wrenches and particularly to the class of sliding jaw wrenches.

One object of the invention is to provide a novel and improved locking means for the sliding jaw which can be easily and quickly released when the jaw is to be moved out of engagement with the work.

Another object is to provide a locking means for the slideable jaw which can be easily and quickly reached for adjustments and repairs.

Other objects and advantages will be apparent from the following description when taken in connection with the accompanying drawing.

In the drawing:

Figure 1 is a side elevation of a wrench made in accordance with the invention partly in section; the cover plate being indicated in dotted lines as thrown back and the locking detent in engaged position.

Figure 2 is a similar view of the intermediate position of the wrench, showing the detent in disengaged position.

Figure 3 is a transverse sectional view on the line 3—3 of Figure 1, passing through the locking detent.

Figure 4 is a transverse sectional view on the line 4—4 of Figure 1.

Figure 5 is a fragmentary rear elevation of the jaw end of the wrench.

Referring particularly to the accompanying drawing, 10 represents a shank having the hand grip 11 on one end and the jaw 12 on the other end. The intermediate portion 13 of the shank is enlarged and formed with a transverse and elongated longitudinally extending opening therethrough shown at 14. Slidable through the enlargement 13 is the shank 15' of the movable jaw 15, said shank having on one of its edge faces the ratchet teeth 16. A removable cover plate 17 is secured over one side of the opening 14, the other side being closed by the side

wall which forms a part of the enlargement. In one wall of the opening 14 there is formed a recess 18 of approximate circular outline, which has an outwardly flaring mouth 19. 60 Disposed within the circular portion of the recess is the rounded head of the member 20, the outer portion 20' having sides 21 which taper inwardly toward the head and permit free rocking movement of the member in 65 the recess. Formed integrally with, or attached, as desired, to the member 20 is a leaf spring 22 which extends to a point adjacent the other end of the opening 14 where one of its flat faces is engaged between the pins 23 carried by the shorter arm of the angle lever 25 which is pivotally supported in the opening 14, at 24. The lever 25 projects through a slot 26 in the rear edge face of the enlargement, and is 70 adapted to be grasped and rocked to cause the pins 23 to flex the leaf spring and rock the member 20 within the recess 18. On the inner end of the member 20 are formed ratchet teeth 27 which engage with the 80 ratchet teeth of the shank 15' of the movable jaw 15. When the pins are in the position shown in Figure 1, the member 20 has its teeth engaged with the teeth of the shank 15', but when the lever is moved to rock 85 the pins into the position of Figure 2 the spring is flexed and the member 20, so rocked as to release its teeth from the teeth of the shank 15', thus permitting the movable jaw 15, and its shank to be slipped inwardly or 90 outwardly, as the case may require.

The outer end of the shank 10 is bifurcated at 10' to receive therein the shank 12' of the jaw 12, which shank is pivotally mounted within said bifurcation for swinging movement toward the jaw 15, its rearward swinging movement being limited by the sleeve 11' of the jaw 15. In the inner end of the jaw 15 is cut a notch or recess 28 into which the shank of the jaw 12 is arranged to move when the jaw is swung in that direction. A recess 29 is formed in the shank 10, inwardly of the inner end of the shank 12', and secured in this recess is a leaf spring 30 whose outer end bears against 100 a lug 31, formed on the inner end of the shank 12', to exert pressure on said shank, for the purpose of yieldably maintaining the jaw 12 in its normal rearward position as shown in Figure 1.

Formed longitudinally through the hand grip 11 and receiving the inner end portion

of the shank 15' is a bore 32 and disposed in this bore and embracing the reduced end of the said shank is a coil spring 33. In the outer end of the bore is screwed a closure 5 plug 34 against which the other end of the spring 33 bears. This spring exerts pressure on the shank 15' so that when the lever 25 is moved to release the teeth 27 from the teeth 16, the spring will force the shank 15' 10 outwardly and thus dispose the jaw 15 against the work.

It will be noted that the ratchet teeth of both the member 20 and the shank 15' are arranged to permit the ready sliding of the shank 15' to move the jaw 15 toward the jaw 12, but will engage each other and prevent movement of the jaw 15 away from the jaw 12, with the result that the jaw 15 may be quickly and easily adjusted to the work, and 20 firmly held in such position. To release the jaw 15, and permit movement thereof, away from the jaw 12, the lever 25 must be swung outwardly through the slot 26, with the result that the leaf spring will straighten out 25 and permit the member 20 to rock and disengage its teeth from the teeth of the shank 15.

By reason of the fact that the jaw 12 is pivotally mounted in the shank 10, permits 30 the said jaw to move into gripping relation to the work, so that the other jaw 15 will be also held against the work. Thus the same jaws serve to operate on nuts and round work, such as bars, or pipes.

35 What is claimed is:

1. A wrench including a shank, a toothed shank slideable in the first shank, a rockable toothed member mounted in the first shank and engaging the teeth of the second shank,

an angle lever mounted in the first shank, 40 and a resilient means secured to the rockable member and loosely engaged with one arm of the lever for moving the rockable member into and out of engagement with the toothed shank. 45

2. A wrench including a shank, a toothed shank slideable longitudinally through the first shank, a rockable toothed member mounted in the first shank and engageable 50 with the toothed shank, a rockable angle lever mounted in the first shank, and a flexible arm secured to the rockable toothed member and operatively engaged with the lever for flexing movement thereby, and movement of the rockable toothed member 55 into and out of engagement with the toothed shank.

3. A wrench including a shank having a longitudinal bore and a lateral recess opening into the intermediate portion of the bore, 60 a toothed shank slideable through the bore with its teeth facing the recess, a toothed rock arm mounted in the recess and engaging with the toothed shank, a cam lever pivotally mounted in the recess, laterally 65 projecting pins on the cam lever, and a leaf spring fixed to the rock arm and frictionally engaged between the said pins, whereby upon rocking movement of the cam lever, the spring will be flexed to rock the rock arm 70 into and out of engagement with the toothed shank.

In testimony whereof, I affix my signature, in the presence of two witnesses.

HERVEY W. SMALL.
